UNITED STATES PATENT OFFICE.

ALLEN S. WISE, OF EAST ORANGE, NEW JERSEY, ASSIGNOR TO WESTINGHOUSE ELECTRIC & MANUFACTURING COMPANY, A CORPORATION OF PENNSYLVANIA.

IRONING MACHINE.

Application filed July 2, 1925. Serial No. 41,002.

My invention relates to ironing machines, and it has a special relation to motor-operated machines.

An object of my invention is to provide 5 a simple combination hand-and-foot control for a movable ironing member.

Another object of my invention is to provide a novel speed-reducing device for transmitting power to a roll from a motor exterior thereto.

A further object of my invention is to provide a simple device for securing the padding on an ironing roll.

A still further object of my invention is 15 to provide a device to facilitate feeding material to an ironing machine that will also protect the hands of an operator or attendant.

A still further object of my invention is 20 to provide interchangeable end members for an ironing shoe.

Referring to the accompanying drawings,

Figure 1 is a rear elevational view of a 25 machine embodying my invention, parts being broken away to facilitate illustration.

Fig. 2 is an elevational view taken at the right-hand end of the machine shown in Fig. 1,

Fig. 3 is a transverse sectional view of an 30 ironing shoe taken substantially on the line III—III of Fig. 4.

Fig. 4 is a rear view partially in section and partially in elevation of an ironing shoe.

Fig. 5 is a view, partially in section and partially in elevation, of a clutch and 35 cooperating parts.

Fig. 6 is a view, partially in section and partially in elevation, showing the parts illustrated in Fig. 5, and driving mechanism 40 for an ironing roll.

Fig. 7 is a view similar to Fig. 2, not showing, however, the supporting standards.

Fig. 8 is a rear view, partially in section 45 and partially in elevation, of the right-hand end of the machine, the greater portion of the shoe being broken away.

Fig. 9 is a view similar to Fig. 7 but showing, however, the shoe in its outer position.

Fig. 10 is substantially an exploded view of clutch parts, the shaft being omitted.

Figs. 11 to 14 inclusive, are detail views 50 of clutch parts.

Fig. 15 is a view of the inner side of the

clutch, parts being broken away to facilitate illustration.

Figs. 16 and 17 are detail views of a sleeve.

Fig. 18 is a detail view of a tube and 60

Fig. 19 is a detail view of a spring and cooperating parts.

Features of a machine embodying my invention are a motor 1 secured to a feed board 2, a roll 3 and a shoe 4. 65

The shoe 4 has a plate 5 adapted to engage the roll 3 for effecting an ironing action. The plate 5 is secured at one end to an end member 6. A rear plate 7 is also secured to the end member 6. Where the 70 end member 6 engages the plates 5 and 7, it is provided with lateral flanges 8 (Fig. 4) against the outer of which a cover 9 is fitted.

The wall directly behind the flange of the 75 end member 6 is also cut away to provide room for nuts 10 which serve as means for securing the plates 5 and 7 to the end member 6. The end member 6 is symmetrical on both sides thereof, with respect to a 80 plane extending longitudinally thereof and may be used at either end of the shoe 4, as it is of the same size and shape as, and interchangeable with a similar end member 11. The location of the nuts 10 facilitates the 85 manipulation thereof from either side of the end member 6. The end member 6 is provided also with oppositely directed bosses 12, in one of which a burner 13 is received. Thus, the end member 6 is adapted also to 90 cooperate with the burner 13 irrespective of the end of the shoe at which it is located.

The end members 6 and 11 have openings to receive a tube 14 to which they are secured. A stub shaft 15 (Fig. 4) is secured in 95 one end of the tube 14 for pivotally mounting the same on a support 16. At the middle of, and within, the tube 14, a shaft 17 is secured by means of a pin 18 (Fig. 1), the shaft 17 projecting from the tube and being 100 secured to a bell crank 20 through which it is coupled, in a manner presently to be described, with power devices for pressing the shoe 4 against the roll 3.

When the shaft 17 is subjected to torque 105 by the bell crank 20, it applies force, through the pin 18, to the tube 14. As the tube 14 is adapted to yield slightly to the torsional stress, it supplies a substantially equal amount of force to the end members 6 and 110

11, and the pressure along the plate 5 is, therefore, balanced.

10 A flexible lip 21 is secured to the leading edge of the shoe 4 and is adapted to engage the roll 3 when the shoe is in engagement therewith.

15 The lip 21 simplifies the feeding of material between the roll 3 and the shoe 4 by first engaging the material and setting up enough adherence or frictional contact between it and the moving roll 3 to cause it to pass in between the shoe and the roll when the shoe is actually in engagement with the roll. This makes it unnecessary to move the shoe away from the roll to introduce the material.

20 The lip 21 also affords a comparatively cool guard against which the operator's fingers may be drawn without danger of burning. The pressure of the lip is light so that, if the operator's fingers are drawn thereunder with the material, he can readily remove his hand without substantial injury.

25 The specific means for supporting the machine on a floor is not essential to the invention.

30 The support 16, in which the stub shaft 15 is journaled, carries the feed board 2 and a shaft 22, also journaled therein, on which the roll 3 is mounted. A support 23 at the other end of the machine is of the same construction as the support 16 and has a similar relationship to the feed board 2. The shaft 17 is journaled in the support 23.

35 The supports 23 and 16 are interchangeable, a feature which makes for economy in manufacture, and are secured to a platform 24.

40 At one end of the platform 24 a block 25 is secured and contiguous thereto is a standard 26 adapted to rest on the floor. The standard 26 has the shape of an isosceles trapezoid and is provided with two inwardly directed flanges 27. The block 25 engages the standard 26 and the flanges 27. At the other end of the machine, a block 28 and a standard 30 are provided to cooperate in the same way as the block 25 and the standard 26. The shape of the standards 26 and 30 renders them interchangeable and they are secured together by an intermediate brace 31 (Fig. 1) and a lower brace 32. The platform 24, together with the supports 16 and 23 and the parts carried thereby, is readily assembled with the standards 26 and 30 by the mere insertion of the blocks 25 and 28 between them.

45 A treadle 33 (Figs. 1 and 2) is secured for pivotal movement about the brace 32 by means of a pair of straps 34 and 35 which are looped over the brace 32. A cable 36 is secured to the treadle 33 for operation in a manner presently to be described. The treadle 33 may be located in the outer position, shown in full lines in Fig. 2, from 50 which it is downwardly movable by the foot

of the operator to lower position. The treadle 33 may also be swung to the upper of the inner positions shown in dotted lines in this figure whence it is depressible to the lower dotted-line position.

55 The movability of the treadle 33 into inner and outer positions facilitates the operation thereof, both when the operator is standing and when he is seated. The function of the treadle is performed by its downward movement, whether it is disposed inwardly or outwardly, but when it is disposed inwardly, it does not project beyond the standards 26 and 30 and the machine is adapted for storing in a minimum of floor space.

60 The roll 3 (Fig. 6) comprises a shell 37 and padding 38 which is wound thereon. For securing the padding 38 to the shell 37, the latter has openings 40 cut therein which are of approximately triangular shape but 65 have two sides which gradually approach to form a slot. The slots point in the direction in which the padding 38 is wound on the roll 3 and in a direction opposite to that of its rotation. To attach the padding 38 to the shell 37, a small bunch 41 of the padding is inserted into each of the openings 40 and drawn into the slot which wedges it and holds it firmly. The padding is then wound about the shell 37 and is securely gripped in 70 the openings 40 and, therefore, does not slip about the shell 37 when the roll 3 is in operation. The shape of the openings 40 is such that the padding is held without tendency to tear or cut the fabric but may be readily released from the openings 40 in an obvious manner.

75 One end of the roll 3 encloses gearing, presently to be described, for rotating the same. A housing 42 is secured to the shell 37 and is 80 rigid with a bearing 43 for supporting the end of the roll 3 on the shaft 22. The housing 42 is adapted to contain lubricant for the gearing.

85 A helical tube 44 (Figs. 6 and 18) extends through a wall of the housing 42 and surrounds the bearing 43. The tube 44 is adapted to permit the escape of expanding gases in the housing 42. If, during the rotation of the roll 3 and the tube 44, lubricant 90 should enter the tube, it cannot escape because the tube rotates with the roll and operates on the principle of an Archimedean screw to return the lubricant to the housing 42.

95 The end of the shell 37 is closed by a cap 45 which fits closely about a sleeve 46 (Figs. 6, 16 and 17) and prevents the escape of lubricant at this point. The sleeve 46 is also provided with a spiral 46^a to prevent creepage of the lubricant along the surface of the sleeve. The sleeve 46 has a pulley 47 secured thereto, and an endless belt 48 extends over the pulley 47 and a pulley 50 mounted on the armature shaft 51 of the motor 1.

The sleeve 46 has a gear 52 thereon which meshes with a planetary pinion 53. The planetary pinion 53 is rigid with a planetary pinion 54, the pinions being mounted 5 for rotation on a stub shaft 55. The ends of the stub shaft 55 are received in openings in a spider 56 which is mounted for rotation on the shaft 22. A pair of planetary pinions 58 and 60, corresponding in construction and 10 operation to pinions 53 and 54 respectively, are also carried by the spider 56. The pinions 53 and 58 mesh with an internal gear 61 which is rigid with the shell 37, and the pinions 54 and 60 mesh with an internal gear 62 15 which is keyed on the shaft 22 by means of a securing portion 63.

The pulley 47 is driven in the direction indicated by the arrows in Fig. 6 by means of the motor 1 acting through the belt 48, to rotate the gear 52. This causes the planetary pinions 53 and 54 to travel with respect to the internal gears 61 and 62. When the shoe 4 is in engagement with the roll 3 and pressed thereagainst, the shaft 22 is held stationary 20 by parts presently to be described. The internal gear 62 is then stationary, and the travel of the planetary pinions 53 and 54 causes a rotation of the roll 3 in the direction indicated by the arrow thereon in Fig. 6. 25 The movement of the roll 3 in the direction indicated is due to the fact that the pinion 53 has more teeth than the pinion 54, and the operation is the result of well known gearing principles. The sizes of the gears 30 illustrated are not essential to the invention but, if the pinion 53 has 28 teeth, the pinion 54 has 26 teeth, the internal gear 61 has 80 teeth and the internal gear 62 has 78 teeth, a proper gear ratio obtains.

As stated, the securing portion 63 of the internal gear 62 is keyed to the shaft 22. The travel of the planetary pinions 53 and 54, in rotating the roll 3 when the shoe 4 is pressed thereagainst, exercises a force on the 40 gear 62 tending to rotate the shaft 22 in a direction indicated by the arrow shown thereon in Fig. 6. This tendency is utilized to maintain the shoe 4 in engagement with the roll 3.

A crank member 64 is mounted on the shaft 22 and may be secured thereto or released therefrom by means of operator controlled clutch parts presently to be described.

The crank member 64 has a pin 65 thereon, 45 on which a link 66 is pivoted, the links 66 having a lug 66' thereon and being pivotally secured to a lever 67. The lever 67 is pivoted on a pin 68 carried by the upper arm 70 of the bell crank 20.

A bolt 71 is pivotally secured to the lower 50 end of the lever 67 and extends through openings in a pair of caps 72 and 73 which engage a spring 74. A pair of nuts 75 and 76 (Fig. 19) on the bolt 71 are adapted to engage the caps 72 and 73 respectively. The

arms of a bolt 77, of U-shape, extend through openings in the caps 72 and 73. A pair of nuts 78 thereon are adapted to engage the cap 72, and a pair of nuts 80 thereon are adapted to engage the cap 73. The bolt 77 70 surrounds the support 23 and exercises a gripping action on a retainer 81 which supports it in position. A bolt 82 (Figs. 7, 8 and 9) is adjustably secured to the support 23 and engages the lever 67 when the shoe 75 4 is pressed against the roll 3. It also serves as a support for casings for the pulleys 50 and 47, as will be hereafter described.

A clutch member 83 is mounted for rotative movement on the shaft 22 and is movable by an operator by means of a handle 84. A rod 85 is pivotally connected to the clutch member 83 and extends through an opening in an arm 86 of the bell crank 20. One end of a spring 87 on the rod 85 engages the arm 86 and the other end engages a collar 88 on the rod.

The handle 84 is movable by the operator into the dotted-line and full-line positions of Fig. 7 and when it is in the dotted-line position of Fig. 7, the parts have the positions shown in full lines in Fig. 9. When the handle is moved rearwardly to the position shown in full lines in Fig. 7, the clutch member 83 and the rod 85 operate after the manner of a toggle and, by means of the spring, 87, depress the arm 86. This causes the arm 70 of the bell crank 20 to move forwardly and to advance the link 66. Force is also transmitted through the shaft 17 which imparts rotative movement to the tube 14 and moves the shoe 4 into engagement with the roll.

When the handle 84 is moved to the position shown in Fig. 9, the spring 87 no longer exerts pressure on the arm 86, and the shoe 4 is permitted to assume the full-line position shown in Fig. 9. The lug 66' on the link 66 limits the downward movement thereof by engaging the crank member 64, so that, when the handle 84 is again moved rearwardly, the pin 65 is above center position, and the advancement of the link 66 is permitted.

The clutch member 83 is provided with a pair of cams 89 (Figs. 10 and 13) adapted to engage pins 90 which extend through openings 90' (Fig. 12) in a clutch member 91. The clutch member 83 has also a lug 92 thereon which is adapted to engage, in one position, a stud 93 on the support 23, and, in another position, a stud 94 (Fig. 6) on the clutch member 91. The clutch member 91 fits about, and is rotatively movable with respect to, a shoulder 95 (Figs. 5, 6 and 10) on the crank member 64 and has a pair of knuckles 96 and 97 (Fig. 15), the latter of which is adapted to engage the crank member 64 and is provided with a stop 98 115 adapted to engage the stud 93. 120 125 130

The cable 36 is secured at 99 to the clutch member 91 and extends therebeyond, being secured to an end of a spring 100 fastened to the feed board 2. A rib 101 on the clutch member 91 serves as a guide for the cable 36 which lies therealong and extends downwardly, through an opening (not shown) in the platform 24, to the treadle 33. The clutch member 91 has an opening 102 therein to receive a guide member 103 (Figs. 5, 6, 10 and 11) which has a pair of openings 104 in which a pair of pins 105 are guided. The pins 105 are insertible into a plurality of openings 106 in the crank member 64 and 15 their tapered ends adapts them for ready retraction therefrom.

The pins 105 are secured to a pair of discs 107 and a spacer 108 disposed therebetween. A plate 110 fits about the spacer 108 and between the discs 107 and is rotatable with respect thereto. The pins 90 are secured to the plate 110 as are also springs 111 which are secured to the clutch member 91 to urge the plate 110 toward it.

25 When the handle 84 is in a position shown in Figs. 5 and 9, the cams 89 engaging the pins 90 hold the plate 110 away from the clutch member 91 and thus retain the pins 105 in retracted position out of the openings 106. The shaft 22 is then free for movement with respect to the crank member 64. When the handle 84 is moved to the position shown in full lines in Fig. 7, the clutch parts assume the position shown in Fig. 6. 35 The cams 89 are moved out of engagement with the pins 90 which are permitted to move because of the urge of springs 111. The pins 105 are then inserted in the opening 106 in the crank member 64 which is 40 thus made rigid with the guide member 103 and the shaft 22.

It is apparent, therefore, that, when the shoe 4 is in its outer position, shown in Fig. 9, and the handle 84 is moved rearwardly, the clutch member 83 is shifted, the rod 85 is depressed, the crank member 20 is moved and the shoe 4 is brought into engagement with the roll 3. During this movement of the clutch member 83, the pins 50 105 are permitted to enter the openings 106, and the crank member 64 is thus clutched to the shaft 22. The engagement of the shoe 4 with the roll 3 throws a load on the motor 1. The motor 1 rotates the roll 3 through the planetary gearing, as described, and, by the reaction set up in the drive and acting through the internal gear 62, the supporting portion 63, the shaft 22 and the crank member 64 urges the link 66 forwardly. As the spring 74 tends to prevent rearward movement of the lower end of the lever 67, the arm 70 is moved forwardly, shoe pressure developing on the roll 3 until the upper part of the lever 67 engages the 65 bolt 82.

When the handle 84 is moved forward to the dotted-line position of Fig. 7, the cams 89 force the pins 90 into the position shown in Fig. 5 and thus retract the pins 105 to de-clutch the member 64. The member 64 is 70 then permitted to move rearwardly with the link 66 and the spring 74 is permitted to expand. The pivotal movement of the lever 67 is yieldingly checked by the bolt 71 which is limited in its movement by the spring 74. 75

When the clutch parts are in the positions shown in Fig. 5, the shaft 22 is, as described, free for rotation with respect to the crank member 64. Since, at this time, the shoe 4 is away from the roll 3, the operator may 80 arrange material thereon and, for this purpose, may move the roll freely forwardly or rearwardly. As the shaft 22 may rotate freely, there is no impedance to the movement of the roll 3, by the operator, in either 85 direction.

The clutch member 91 is movable to effect a declutching action when the parts are in the positions shown in Figs. 2 and 7. To perform this operation, the operator depresses the treadle 33 and, by means of the cable 36, imparts rotative movement to the clutch member 91 against the action of the spring 100. The clutch member 91 moves in a direction indicated by the arrow thereon in Fig. 6 and causes the pins 90 to ride on the surface of cams 89, thus moving them laterally to the position shown in Fig. 5 and retracting the pins 105 from the crank member 64. In the movement of the clutch member 91, the knuckle 97 thereon engages the crank member 64 to move it rearwardly. A movement of the link 66 also occurs and the lever 67 is swung about its pivot. Since the movement forwardly of the lower end of the lever 67 is limited by the bolt 71, the arm 70 of the bell crank 20 is moved rearwardly and the shoe 4 is lifted out of engagement with the roll 3, thus permitting the insertion of material under the shoe 4 by the 105 operator. 110

The spring 87 remains under compression and, when the operator permits the treadle 33 to rise, it returns the shoe 4 to engagement with the roll 3. At the same time, the spring 100 acts upon the clutch member 91 and moves it rotatively in a reverse direction, and the stop 98 engages the stud 93. 115

In addition to the described function of the bolt 82 in stopping the lever 67, it serves as mentioned, as a support for casings 112 and 113. As shown in dotted lines in Figs. 7 and 9, a nut 114 on the bolt 82 engages a strap 115 and holds it against the support 23. The strap 115 has an opening 116 (Fig. 125 8) which receives a pair of lugs 117 on the casings 112 and 113. The casings 112 and 113 are supported by a bolt 118 extending therebetween from the support 23 and surround the pulleys 50 and 47 and the belt 48 130.

and are provided, at their other ends, with lugs 119 which are secured together by a loop 120. The casings 112 and 113 may readily be removed by detaching the loop 120 and 5 withdrawing the lugs 117 from the opening 116. The assembly of the casings 112 and 113 may be made in an obvious manner. The casings 112 and 113 are similar in shape and are interchangeable, a feature 10 which makes for economy in manufacture.

The co-relations of the various functions of the machine will now be described.

When the parts are in the position shown in Fig. 9, and it is desired to effectuate an 15 ironing action, the handle 84 is moved rearwardly to depress the rod 85 and thereby causes the shoe 4 to engage the roll 3. At the same time; the movement of the cams 89 with respect to the pins 90 permits the 20 pins 105 to move from the position shown in Fig. 5 into the position shown in Fig. 6 wherein they are received in the openings 106. The crank member 64 is thus clutched to the shaft 22 which is brought to a stop.

25 When the parts are in the position shown in Fig. 9, if the operator's hands should be encumbered with material to be ironed making it inconvenient to effectuate ironing by movement of the hand control, then he may 30 actuate the treadle 33 instead. Depression of the treadle 33 operates by means of the cable 36 to rotate the clutch member 91 and thus advance the stud 94 (Fig. 6), into engagement with the lug 92 whereby the 35 clutch member 83 is moved and the rod 85 is carried downwardly to the position shown in Fig. 7. Thereafter on the release of the treadle 33 the clutch member 91 returns to its initial position, the clutch then being in the 40 "in" position.

The motor drive is then effective, through the planetary gearing, to rotate the roll 3 and, by the reaction developed on the internal gear 62 and transmitted by the securing portion 63 thereof to the shaft 22, to 45 exercise a force on the crank member 64 tending to urge it forwardly.

The reactive force exerted on the crank member 64 is transmitted through the link 50 66 and the lever 67 to the shoe 4 but the pressure is not permitted to rise beyond a predetermined point for when the lever 67 is pressed against the bolt 82 on the forward movement of the crank member 64, it prevents a further forward movement of the 55 arm 70 of the bell crank 20. After the engagement of the lever 67 with the bolt 82, any additional force tending to move the crank member 64 forwardly of the position 60 shown in Fig. 7 would cause the lever 67 to fulcrum on the bolt 82 and to move the pin 68 rearwardly, thereby moving the shoe 4 rearwardly and decreasing the shoe pressure.

65 The principle of reaction by which the

shoe 4 is pressed against the roll 3 is similar to that described in my copending applications, Serial Nos. 715,105 and 715,106, both filed May 22, 1924.

As stated, the bolt 82 is adjustable so 70 that, when moved to a rearward position, the ironing pressure will be decreased, and, when moved to a forward position, the pressure will be increased, since the arm 70 and the upper part of lever 67 may then move forwardly a greater distance. 75

To release the ironing shoe 4, the operator moves the handle 84 forwardly from its rear-most position and, by means of the cams 89, declutches the crank member 64 in the manner described. The expansion of the spring 74 then tends to throw the upper portion of the lever 67 rearwardly and operates, in conjunction with the action of gravity, to move the shoe 4 to its outer position. 85

As described, the treadle 33 may be depressed when the shoe 4 is in engagement with the roll 3, thus moving the clutch member 91 to declutch the crank member 64 and, by means of the knuckle 97, move the crank 90 member 64 rearwardly and to lift the shoe 4 out of engagement with the roll 3. When the operator permits the treadle 33 to rise, the clutch member 91 is moved in a reverse direction by the spring 100, and the crank 95 member 64 is reclutched. The reaction then developed by the planetary gearing, as described, maintains the shoe 4 pressed against the roll 3.

The invention is not limited to the described details of construction and operation but the embodiment disclosed is capable of extensive modification without departing from the spirit of the invention. For instance, a gear or worm drive may be substituted for the belt 48. A substantial range of equivalents is contemplated within the scope of the appended claims. 100

I claim as my invention:

1. The combination of an ironing roll, 110 an ironing shoe movable towards and from said roll, power means for rotating said roll, said shoe being movable against said roll by the direct-exercise of force by an operator, and means operative when said shoe is 115 against said roll to transmit power from said power means to said shoe for pressing said shoe against said roll.

2. The combination of an ironing roll mounted for rotation, an ironing shoe movable towards and from said roll, power means for rotating said roll, said shoe being movable by the direct exercise of force by an attendant against said roll, and means operative by reaction developed in the rotation 120 of said roll by said power means to press said shoe against said roll. 125

3. The combination of an ironing roll, an ironing shoe movable towards and from said roll, power means for rotating said roll, 130

resilient means operable manually for moving said shoe against said roll and means operable when said shoe is against said roll for transmitting power from said power means for pressing said shoe against said roll.

4. In an ironing machine, the combination of a rotatable shaft, a roll rotatably mounted thereon, an ironing member movable towards and from said roll, a motor exterior of said roll, means operable by said motor for applying force to said shaft at a point interiorly of said roll for rotating said shaft and means operable by said shaft to press said ironing member against said roll.

5. In an ironing machine, an ironing roll, a flexible covering for said roll and means for securing said covering to said roll comprising a plurality of slots of substantially triangular shape formed in the peripheral surface of said roll, the flexible covering being wedged in said slots.

6. In an ironing machine, the combination of a pair of ironing members one of which is movable towards and from the other, a tube having its ends secured to the movable member and supporting the same, a member extending into said tube and secured thereto intermediately of its ends and means for applying rotative force to the last mentioned member and thereby pressing said movable ironing member against said other ironing member.

7. In a machine, the combination of a motor, a member movable thereby and a pivoted treadle for controlling the movement of said member by said motor, said treadle being movable about its pivot point into two inactive positions and being movable immediately from either of said positions into an active position.

8. In an ironing machine, the combination of a pair of standards, a treadle pivoted thereon for movement into an inner and an outer position, an ironing member and means operative by an immediate movement of said treadle in either of said positions to move said ironing member.

9. In an ironing machine, the combination of a rotatable roll, a heated shoe and a flexible lip secured to the leading edge of said shoe and engaging said roll for facilitating the feeding of articles between said shoe and said roll.

10. An ironing shoe, the combination of an elongated member having an ironing surface and a pair of end members secured thereto for supporting the same, each of said end members being interchangeable and symmetrical with respect to a plane at right angles to the longitudinal axis of the elongated member.

In testimony whereof, I have hereunto subscribed my name this 25th day of June, 1925.

ALLEN S. WISE.
